UNITED STATES PATENT OFFICE.

MINOTT W. SEWALL, OF ROSELLE, NEW JERSEY, ASSIGNOR TO THE BABCOCK & WILCOX COMPANY, OF BAYONNE, NEW JERSEY, A CORPORATION OF NEW JERSEY.

WATER-TUBE BOILER.

986,089.

Specification of Letters Patent. Patented Mar. 7, 1911.

Application filed June 21, 1909. Serial No. 503,304.

To all whom it may concern:

Be it known that I, MINOTT W. SEWALL, a citizen of the United States, residing at Roselle, in the county of Union and State of New Jersey, have invented certain new and useful Improvements in Water-Tube Boilers, of which the following is a specification.

In my application Serial No. 501,751, filed June 12, 1909, I have described a water tube boiler comprising substantially vertical uptake and downtake manifolds each of which has an upward extension above the water line.

The present invention relates to a boiler of the type described in that application, the object being to provide means within the manifolds to effect the removal of the salts of lime and magnesia, or other impurities, from the feed water, and the deposit of such impurities in the bottom of one of the manifolds from which they may be blown out.

The usual method of operation of a boiler is to discharge the feed water directly into the boiler circulation, or to discharge it into the common steam space of the boiler where it becomes partially heated and then minglest freely with the boiler circulation, the result being that the separation of the contained impurities takes place largely within the tubes and is deposited on their internal surfaces as a hard scale.

In order to effect the purification of the feed water, according to the present invention, before its admission to the boiler circulation, it is necessary that it be heated and then conveyed to a settling chamber. The form of the manifolds described in my said application Serial No. 501,751 permits of their utilization to effect both of these operations. By reason of their extension upwardly a heating space for the feed water separate from the boiler circulation is afforded in either or both manifolds, and into such space or spaces I introduce means for the requisite heating of the feed water. By a vertical partition in the downtake manifold a settling chamber is provided, so that the water may be heated and then allowed to remain in a quiescent state a sufficient length of time and under favorable conditions for the separation of impurities. The water is passed from the settling cham-

ber through an opening of ample area for a slow movement into the circulatory system 55 comparatively free from scale-forming matter. The purification of the feed water by the present invention comprises, therefore, the heating of the water and the separation of the impurities therefrom within the boiler 60 structure but separate from the circulation, and will be understood from the following description.

In the accompanying drawings, forming a part of the specification, Figure 1 is a side view partly in section of a boiler, the furnace and boiler setting being omitted; Fig. 2 a horizontal section on the plane of the line 2—2 of Fig. 1; and Fig. 3 a diagrammatic view of a modification, and Fig. 4 a 70 section on the plane of the line 4—4 of Fig. 1.

Similar reference numerals indicate similar parts in the several views.

Referring to the drawings, the numeral 1 75 designates the uptake manifold, 2 the downtake manifold, 3 the bank of inclined tubes expanded into the manifolds and forming the heating surface, and 4 the substantially horizontal circulation tubes through which 80 mingled steam and water from the tubes 3 pass from the uptake to the downtake manifold completing the cycle of circulation. Both manifolds are substantially cylindrical and extended above the water line, established by the circulating tubes 4, to provide 85 steam drums or chambers separate and distinct from the boiler circulation. These chambers contain means for heating the feed water and delivering it to the boiler circulation as follows. In the uptake manifold the drum or chamber is formed by a partition 5 extending across the manifold above the water line, said partition having an opening or openings 6 to admit boiler steam 90 to the chamber. Into the chamber thus formed is admitted a feed water supply pipe 7 which is turned upwardly and discharges in proximity to the dome of the manifold. Any suitable spraying or distributing means may be employed to subdivide the water and to bring it into intimate contact with the steam. As shown, I provide a plate 8 upon which the incoming water falls and beneath said plate a series of 100 plates 9 supported in any suitable manner

and preferably increasing downwardly in diameter. The plates 9 are comparatively shallow so that the water will be spread out upon them into a thin sheet and overflowing the lowermost will fall upon the partition wall 5. The latter is preferably inclined slightly and, connecting with the chamber above said plate, is a delivery pipe 10 to convey the feed water to the downtake manifold.

The downtake manifold above the heating tubes 3 is enlarged, as shown in Fig. 1, and said manifold is divided longitudinally by a wall 11 extending from the base to above the water line, thus forming two chambers 12 and 13, the former of which is the downtake discharge for the boiler circulation, and the latter a quiescent sediment chamber for the feed water and into which the pipe 10 discharges. Below the discharge opening of said pipe is arranged an inclined plate 14 from which the water falls. To increase the rapidity of heating there is placed on top of the plate 14 corrugated wire netting, or similar material, which will cause a roughening of the surface of the water and provide metal parts which project into the live steam for conveying heat into the body of flowing water. The vertical partition wall 11 is provided with an opening 15 and from the upper edge of said opening a lateral wall 16 is projected into the chamber 13. The opening 15 is comparatively large in area to prevent any disturbance of the water in its passage through it. Substantially all of the supply to the water of circulation will pass through this opening, it being, in fact, the feed connection to the boiler proper. The sediment chamber 13 is made convergent downwardly by means of a wall 17, and from the bottom of said chamber leads a blow-off connection 18. A blow-off connection 19 leads from the circulation chamber on the opposite side of the wall 11.

The sediment chamber 13 is separated from the steam chamber in the upper part of the downtake manifold by a horizontal wall 20 extending from the partition wall 11 and is provided with an opening or openings 21 to equalize the steam pressure in the two chambers. Pipe 10 has an enlarged section to allow of the settlement of such matter as is precipitated from the water during its passage through the pipe, the sediment being drawn off through a pipe 22.

The operation will be readily understood from the foregoing description. The incoming feed water is discharged through the pipe 7 and flows over the plates 8 and 9 onto the partition 5, through pipe 10 into chamber 13, receiving heat throughout its entire passage. The inflowing water is mingled with that in chamber 13 which has a gradual

downward movement to the opening 15. The water in chamber 13, being in a quiescent state, will permit the settlement of any solid particles in suspension, and the clarified water to pass into the circulation. The sediment will collect in the converging bottom of the manifold and may be blown off through pipe 18. The settling chamber has a common water line with the boiler water and this remains common irrespective of the height of the water in the drum, that is as the water in the said chamber rises and falls with that in the boiler proper, a portion of the water in the settling chamber is available for maintaining the water level of the boiler.

In Fig. 3 the water delivery pipe 10 from the uptake manifold discharges into a closed chamber 23 formed by partition walls 24 and 25. Instead of extending the partition wall above the water line as in Fig. 1, I divide the downtake manifold by a partition 26 which terminates below the water line, and the feed water is discharged into the sediment chamber 13 through a pipe 27 forming the outlet from chamber 23 and extending downwardly to the lower part of the sediment chamber. In this form the water passes from the sediment chamber upwardly over the top of the vertical partition wall 26 into the boiler circulation.

What I claim and desire to secure by Letters Patent of the United States is:—

1. A water tube boiler comprising a manifold for the reception of water-heating tubes, said manifold having a chamber formed therein, means for admitting feed water to said chamber and for heating it therein, and means for conveying the feed water away from said chamber to the boiler circulation.

2. In a water tube boiler, a manifold for the reception of water-heating tubes, said manifold having a steam chamber above the water line, a feed water supply connecting with said steam chamber, means for receiving the incoming water so arranged as to present a large and thin surface of over-flow water to the steam, and means for conveying the feed water away from said chamber to the boiler circulation.

3. In a water tube boiler, a manifold for the reception of water-heating tubes, a partition across said manifold above the water line to form a chamber in the upper part of the manifold, means for admitting feed water to said chamber and for heating it therein, and means for conveying the feed water from said chamber to the boiler circulation.

4. In a water tube boiler, a manifold for the reception of water-heating tubes, a partition across said manifold above the water

line to form a chamber in the upper part of the manifold, means for admitting feed water and boiler steam to said chamber to heat the feed water, and means for conveying the feed water from said chamber to the boiler circulation.

5. In a water tube boiler, a manifold for the reception of water-heating tubes, a partition across said manifold above the water line forming a chamber in the upper part of the manifold, means for admitting feed water and boiler steam to said chamber, and a distributing surface in said chamber to cause the steam to contact with the feed water.

6. In a water tube boiler, uptake and downtake manifolds having steam chambers above the water line, means for admitting feed water to the steam chamber of the uptake manifold, and a pipe connecting said chambers to deliver the feed water to the downtake manifold.

7. In a water tube boiler, uptake and downtake manifolds, partitions in said manifolds to form chambers separating them from the circulatory portions of the manifolds, means in both chambers for heating feed water admitted thereto; a tube connecting the uptake chamber with the downtake chamber, and means for admitting the feed water from the latter chamber to the boiler circulation.

8. In a water tube boiler, a manifold for the reception of water-heating tubes, a partition dividing said manifold into separate chambers, one for the circulation and the other for a quiescent water reservoir, and means for admitting water from the latter to the former chamber.

40 9. In a water tube boiler, a manifold for the reception of water-heating tubes, means for admitting feed water thereto, a partition in said manifold to form a settling chamber for the feed water, and a blow-off pipe for said chamber.

50 10. In a water tube boiler, a manifold for the reception of water-heating tubes, a partition dividing said manifold into chambers having a common water level, and means for admitting feed water to one of said chambers and from the latter to the other chamber.

55 11. In a water tube boiler, uptake and downtake manifolds for the reception of water-heating tubes, means in the uptake manifold for heating the incoming feed water, means for conveying the water from the uptake to the downtake manifold, means for further heating the water in the downtake manifold, and a settling chamber in the downtake manifold separate and distinct from the water circulation.

60 12. In a water tube boiler, uptake and

downtake manifolds each having an upward extension above the water line to form a steam chamber, means for admitting feed water into and heating the same in the chamber of the uptake manifold, a tube connecting said chambers above the water line, a partition in the downtake manifold to form a quiescent chamber for the feed water, and means for admitting the feed water from said last-named chamber to the boiler circulation.

13. A water tube boiler comprising a manifold for the reception of water-heating tubes, means for admitting water to said manifold and heating the same separate from the boiler circulation, means for causing the separation of the impurities from the heated water, and means for conveying water to the boiler circulation after the separation of the impurities therefrom.

14. In a water tube boiler, uptake and downtake manifolds both having water heating chambers therein separate from the circulation, means for conveying the water from the uptake heating chamber to the downtake heating chamber, a partition dividing the downtake manifold into chambers one of which serves as a settling chamber, and means for admitting the water from the latter to the boiler circulation.

15. In a water tube boiler, a manifold having a substantially closed chamber in its upper part, a partition extending downwardly from said chamber and separating the manifold into two substantially vertical spaces in one of which is contained water of circulation and the other feed water, said partition having an opening so conformed as to direct the feed water in its downward course away from the partition and in its upward course close to the partition and through said opening into the space containing the boiler circulation.

16. In a water tube boiler, a manifold having a partition separating it into two spaces in one of which the feed water is substantially quiescent, and the other of which is open to the boiler circulation, both of said spaces being within the manifold into which the heating tubes are expanded and in which there exists the same water level and the common pressure due to the boiler.

17. In a water tube boiler, a manifold having a partition separating it into two spaces in one of which the feed water is substantially quiescent, and the other of which is open to the boiler circulation, means for introducing the feed water into the lower part of the quiescent chamber, and means for admitting the water from said chamber to the circulation at a point above the point of admission of the feed water into the quiescent chamber.

18. In a water tube boiler, a manifold having two separate chambers one of which chambers is separate from the boiler circulation and the lower part of which is made 5 convergent, and a blow-off pipe at the bottom of said chamber.

In testimony whereof I have hereunto

signed my name in the presence of two subscribing witnesses.
